(57) **CLAIM**

The ornamental design for a shoe, as shown and described.

DESCRIPTION

FIG. 1 is a top, left, and front perspective view of an ornamental design for a shoe;

FIG. 2 is a top plan view of the shoe of FIG. 1;

FIG. 3 is a left side elevational view of the shoe of FIG. 1;

FIG. 4 is a top, left, and front perspective view of the ornamental design for a shoe, according to a second embodiment;

FIG. 5 is a top, left, and front perspective view of the ornamental design for a shoe, according to a third embodiment; and,

FIG. 6 is a right side elevational view of the ornamental design for a shoe, according to a fourth embodiment. The dash-dash-dash broken lines are included for the purpose of illustrating portions of the shoe that form no part of the claimed design. The dash-dot-dash lines are included for the purpose of illustrating boundary lines and form no part of the claimed design.

1 Claim, 6 Drawing Sheets
